OF BROOKLYN, NEW YORK, A CORPORATION OF WEST VIRGINIA.

RETARDING DEVICE FOR AUTOMOBILE TORPEDOES.

1,112,014.

Specification of Letters Patent.

Patented Sept. 29, 1914.

Application filed January 14, 1914. Serial No. 812,167.

To all whom it may concern:

Be it known that I, FRANK M. LEAVITT, a citizen of the United States, residing at Smithtown, in the county of Suffolk and State of New York, have invented certain new and useful Improvements in Retarding Devices for Automobile Torpedoes, of which the following is a specification.

In an automobile torpedo, it is desirable to delay certain of the functions, and for this purpose retarding devices are used. One desirable use of such a retarder is for delaying the ignition of the fuel in the air heater (or so-called "superheater") by which the air at reduced pressure is heated during its flow from the compressed air reservoir to the engine or turbine. It is essential to successful ignition that the igniting cartridge shall not be fired until after the liquid fuel which is forced to the heater shall have reached it through the customary spray nozzle, so that there is instituted a suitable spray of the fuel to insure its ignition when the flame from the cartridge strikes it. The purpose of this retardation is the application of the present invention, which is specifically illustrated.

In the accompanying drawings,—Figure 1 is a sectional side elevation of a portion of the torpedo showing in elevation the several apparatus to which the invention relates; Fig. 2 is a vertical section on a larger scale showing the apparatus at the instant of starting; Fig. 3 illustrates a part of Fig. 2 showing the apparatus at the end of the retarding operation.

In the drawings, A is the shell or hull of the torpedo, of which B is the compressed air flask or reservoir, C is the starting valve, D is the pressure reducing valve, E is the air heater, F is a diagrammatic illustration of the propelling engine in the form of a turbine, and G is the propeller shaft.

The retarding device as a whole is lettered H. It is shown as mounted on a frame or bracket a fastened to the bulk-head b; but any other mounting may be substituted.

The igniter I for the heater E is operated by high pressure air conducted through tubes c and d, the former leading from beyond the starting valve to the retarder, and the latter from the retarder to the igniter. The retarder comprises a valve shell e having an inlet communicating with the tube c and an outlet communicating with the tube

d, and having a seat at this outlet against which closes a valve e. This valve is shown in Figs. 2 and 3 as a cone or tappet formed on a cylindrical plunger e', which latter makes a close sliding fit with the chamber or cylinder f in the shell. The pressure admitted from the pipe c insures the closing of the valve tightly against its seat, so that no air can pass through the tube d until the valve is opened.

The opening of the valve is controlled by the retarding device proper, which comprises a plunger or slide for opening the valve, a friction roller driven at a slow speed from the engine, and a moving part or traction bar displaced by the roller and which after a given movement permits the plunger to move to open the valve.

The valve is opened preferably by a plunger g which receives the air pressure upon its upper end, and upon an annular shoulder between its larger part above and its smaller part or neck beneath. The neck passes out through a close fitting opening in a plug h, and its lower end rests upon a slide i moving freely in the shell f and carrying an idler roller k. This roller normally rests upon a traction bar J which is supported on a friction roller m. The latter is carried upon a shaft n on which is fixed a worm wheel p driven from a worm q, which in turn is driven through gearing from the engine F or shaft G. The gearing shown consists of a gear-wheel r on this shaft meshing with a pinion s on the worm shaft q.

The traction bar J is reduced in width at t, or essentially is formed with a recess or cut away portion which after a certain movement permits the upper roller k to drop into this recess, as shown in Fig. 3. This permits the slide i and plunger g to descend. The descent of the plunger is due to the unbalanced pressure upon it of the compressed air entering from c. The plunger has a pin-and-slot connection or any other suitable lost motion engagement with the valve e, so that its descent pulls down the valve as shown in Fig. 3, thereby opening a passage through the valve and between it and its seat, so as to permit of free flow of air from the tube c to the tube d and the igniter. Upon the descent of the plunger its cone shoulder seats against a coned surface in the top of the plug h so

as to prevent leakage of air around the plunger stem.

The igniter I may be variously constructed. The one shown has an outer shell u seated in a neck in the head of the heater and receiving air from the tube d behind a plunger v which is held back by a spring v' until upon the admission of the high pressure air this plunger is violently pushed forward so that the hammer w which it carries strikes a blow against the cap of the cartridge x and explodes the latter. This igniter is of a known construction.

In operation, when the torpedo is launched the starting valve C is opened in a known manner, thereby admitting compressed air through the pressure regulator D and thence at lower pressure through the heater E to the engine. At the same instant high pressure air passes through tube c to the valve e, where it is arrested until the retarder has performed its movement. When the air reaches the engine F the latter starts, and turning the shaft G with an accelerated movement, drives through the train the friction roll m. The parts are shown in Fig. 2 as at the instant of starting. The roll m propels the traction bar J in the direction of the arrow and against the pull of a spring y. After the bar has moved a certain distance its recess t passes under the roller k and permits the latter to fall thereby opening the valve e and admitting air to the igniter. After this function has been performed it is a matter of indifference whether the traction bar J continues to be moved or whether sufficient looseness is provided so that there is no longer a sufficient tractive effect to carry it beyond the position shown in Fig. 3.

The duration of retardation is determined by the gear ratio and the distance between the initial point of contact between the roller k and bar J shown in Fig. 2, and the location on the bar of the recess t which drops this roller. The bar J starts from a determined starting point. If it is desired in any instance to vary the duration of retardation, this starting point is to be varied. A suitable means for this purpose is provided in an adjustable stop K against which in resetting the device the traction bar is drawn back by its spring y. For this purpose the traction bar has a shoulder J' which strikes the stop; and by adjusting the stop to one position or another the extent of movement of the traction bar between its starting position and its releasing position may be determined. To facilitate

this adjustment the stop K is shown as 60 made in the form of a lever with its lower arm serving as a pointer traversing an arbitrarily graduated scale on a bracket z, to serve as a guide in the adjusting, and with a set-screw z' for clamping it in position 65 after adjusting. The pressure exerted by the compressed air through the plunger g, slide i and roller k, forces the traction bar J into effective frictional engagement with the roller m, so that the turning of the roller 70 displaces the bar without slip.

The device as shown is constructed with the utmost compactness and with a view to meeting the peculiar conditions existing in an automobile torpedo. The device is 75 possibly applicable to other uses, in which case it may be redesigned or reportioned to suit the new conditions.

The invention is not limited to the precise details of construction, but is susceptible 80 of a considerable degree of modification, as will be obvious to those skilled in the art.

I claim as my invention:—

1. A retarding device comprising a traction bar, two rollers on opposite sides of said bar, gearing for driving one roller for displacing the bar, the bar having a recess in which the other roller may fall, and a part the movement of which is to be retarded connected to said latter roller. 90

2. A retarding device comprising a traction bar, two rollers on opposite sides of said bar, gearing for driving one roller for displacing the bar, the bar having a recess in which the other roller may fall, a part the 95 movement of which is to be retarded connected to said latter roller, and an adjustable stop for varying the starting point of said traction bar to adjust the duration of retardation. 100

3. The combination with a valve shell having inlet and outlet openings, a valve moving in said shell to close said outlet, a plunger exposed to fluid pressure within said shell and connected to the valve so that when moved by such pressure it will open the valve, and a retarding device for temporarily sustaining said plunger against such pressure to retard the opening of said valve. 105

In witness whereof, I have hereunto signed my name in the presence of two subscribing witnesses.

FRANK M. LEAVITT.
